CONTROL SYSTEM

Harry B. Holthouse, Jr., Chicago, Ill., assignor to
Motorola, Inc., a corporation of Illinois

Application November 2, 1942, Serial No. 464,270

4 Claims. (Cl. 219—39)

1

This invention relates generally to control systems and in particular to a control system for starting and operating an electrically operated heating system of combustion type.

Electrically operated heating systems generally include a resistance means of some kind for preparing and/or igniting a combustible mixture for burning. In these systems, and particularly those in which the supply of electrical energy for the resistance means is variable, many difficulties are encountered in starting combustion of the mixture. Where the source of electrical supply for the heating system is a battery, the effective capacity of which varies between a high and low charge condition of the battery, these difficulties are further increased with the operation of the heating system at cold temperatures because of the reduction in the effective capacity of the battery with cold temperatures. Thus a control system capable of satisfactorily operating a battery-operated heating system at relatively warm temperatures and with a normal charge on the battery, may be completely ineffective to operate the heating system at temperatures of 0° F. and less due to the reduced effective capacity of the battery and the increased heat demand required of the resistance means to operate at an optimum temperature at cold temperatures. Many efforts have been made to overcome these difficulties but so far they have been unsuccessful.

It is an object of this invention therefore, to provide a control system for a battery-operated heater of combustion type which is adapted to positively start the heater under cold temperature conditions.

Yet another object of this invention is to provide a control system for a heater of combustion type having a battery as the sole source of power supply, which is capable of positively operating the heating system over a wide range of variations in the effective capacity of the battery.

A further object of this invention is to provide a control system for a heater apparatus having a battery as the only source of power and resistor means for heating a combustible mixture to initiate combustion, which is adapted to vary the application of the battery energy on the resistor means so that it will operate to heat the mixture to an optimum temperature for all charged conditions of the battery.

A feature of this invention is found in the provision of a control system for a battery-operated heater of combustion type having resistor means for heating a combustible mixture

2

to an optimum temperature to initiate combustion, in which second resistor means series connected with the heating resistor is adapted to be cut out of the operating circuit of the heating resistor to boost the supply of battery energy to the heating resistor when the energy supplied to the heating resistor through the second resistor is insufficient to operate the heating resistor to heat the combustible mixture to an optimum temperature.

Yet another feature of this invention is found in the provision of a control system for a battery-operated heater apparatus having a resistor for heating a combustible mixture to an optimum temperature to initiate combustion, in which resistance means associated with the operating circuit of the heating resistor is arranged between the battery and the heating resistor to control the application of the battery energy on the heating resistor such that it may be operated to heat the combustible mixture to an optimum temperature for wide variations in the effective capacity of the battery.

Further objects, features and advantages of this invention will become apparent from the following description when taken in connection with the accompanying drawings in which:

Fig. 1 is a longitudinal sectional view of a heater apparatus adapted to be operated by the control system of this invention, showing the combustion portion of the heater apparatus in development;

Fig. 2 is a transverse sectional view of the combustion portion of the heater apparatus as seen along the line 2—2 in Fig. 1;

Fig. 3 is a longitudinal sectional view showing in detail a fuel conditioning unit for the heater apparatus;

Fig. 4 is a diagrammatic control circuit showing one embodiment of the control system of this invention;

Fig. 5 is a diagrammatic control circuit showing a modified form of the invention; and

Fig. 6 is a diagrammatic control circuit showing yet another modification of the invention.

This invention is illustrated in the drawings as applied to a battery-operated heater of internal combustion type having a combustion portion and an air and fuel mixing or conditioning portion connected with the combustion portion to prepare a combustible mixture for burning in the combustion portion. The mixing portion includes a combination heating and igniting unit having a heating coil which heats the fuel to at least a fuel vaporizing temperature for mixing

with the air in the conditioning portion, and then ignites the vaporous air and fuel mixture for burning in the combustion portion. In order to quickly and positively start a burning of the mixture in the combustion portion it is necessary that the heating coil be operated to heat the fuel in as short a time as possible to thoroughly vaporize the fuel for mixing with the air. Any delay in the initial preparing of the combustible mixture, or a failure of the heating coil to heat the fuel to at least a vaporizing temperature, of course will prevent an immediate starting of the heater or any starting at all. The heat generated by the coil is dependent upon its resistance characteristics and the amount of energy applied on the coil from the battery. Thus a battery having a normal pressure of twenty-four volts might vary from a high charge condition of thirty volts to a low charge condition of about eighteen volts. A coil constructed to operate at twenty-four volts might thus operate satisfactorily between twenty-four volts and thirty volts but at eighteen volts would not operate at all, or would take considerable time in reaching an optimum temperature to prepare the fuel for burning. A coil capable of being heated to substantially a maximum temperature at eighteen volts would operate at an overload above this voltage and would burn up when thirty volts were applied to it. These difficulties are overcome in the present invention by the provision of a control system which includes the heating coil and resistance means for varying the energy applied to the heating coil from the battery. Since the energy or effective capacity of the battery varies with its charged condition and with temperature conditions, the coil is constructed to operate with a maximum heat output at the lowest charged condition of the battery, with the resistance means at normal and high charge conditions of the battery being connected with the heating coil so that only a part of the battery charge is applied on the heating coil. On starting of the heater the energy applied to the heating coil is reduced by the resistance means. Should this energy be insufficient to operate the heating coil at an optimum temperature for heating and igniting the air and fuel supplied to the conditioning portion, the resistance means is cut out of the operating circuit for the heating coil so that all of the battery energy is applied to the coil to boost its heat output. It is to be understood, of course, that even though the battery might be at a normal voltage its effective capacity may be reduced with cold temperatures to a value such that it may be necessary to apply the full voltage of the battery on the heating coil at cold temperatures. As a result, a normal operation of the heating coil is provided over a wide variation in the values of the effective capacity of the battery so as to assure a positive and quick starting of the heater.

Referring to Fig. 1 the heater apparatus to which the control system of this invention is applied is shown as including a housing 10 which is divided longitudinally over substantially its entire length by a vertically extending partition member 11 into a mechanical compartment 12 and a heating compartment 13. Within the heating compartment is a substantially cylindrically shaped combustion chamber 14, shown in development in Fig. 1 for the purpose of clarity, which is closed at one end by a cover plate 16 and at its opposite end by the bottom 17 of a substantially cup-shaped member 18. The cup member 18 defines in part an air supply chamber 19 which

5 is in axial alignment with the combustion chamber 14.

10 The combustion chamber 14 is longitudinally divided into four axially extending but connected passages 21a-21d by a partition member 22 of substantially X-shape (Figs. 1 and 2). The combustion chamber inlet 23 and outlet 24 are in the bottom portion 17 of the cup-shaped member 18 and in communication with the passages 21a and 21d, respectively. Located within the inlet 23 is an air and fuel mixing means, indicated generally as 25, which will be later fully explained. The outlet 24 is connected with a tail pipe assembly 26 extended outwardly from the housing 10 through the air supply chamber 19.

15 The outer wall or body portion of the combustion chamber 14 (Fig. 2) is integrally formed with alternately arranged peripheral portions 27 and doubled fin portions 28 which are angularly spaced about the combustion chamber and extended axially thereof. Side portions of the partition member 22 are located within the inner open ends of certain ones of the fins 28 and held in a fixed position relative to the combustion chamber body portion. The fins 28 have a sleeve 29 positioned about their outer closed ends to form an annular passage 31 about the combustion chamber 14 for air to be heated.

20 The air to be heated enters the housing 10 through an inlet 32 opening into the mechanical compartment 12 and is moved by a fan 33 into a chamber 34 connected with the air passage 31. The fan 33 is mounted on the shaft 35 of a motor 30, with both the fan 33 and the motor being located in the mechanical compartment 12. The air from the passage 31 is discharged through an outlet 36 connected with the space to be heated. The compartment 12 and the air chamber 34 are separated from the air supply chamber 19 by a partition member 37 positioned transversely of the housing 10 and about the open end of the cup-shaped member 18. The member 18 cooperates with the partition member 37 and housing end structure 20 to define the air supply chamber 19. Air to the air supply chamber 19 is supplied by a fan 38 mounted on the motor shaft 35 which is journaled in the partition plate 37. An inlet 39a to the fan 38 is provided in the housing end structure 20. The fans 33 and 38 are thus concurrently operated by the motor 30.

25 The motor 30 also operates a fuel pump 39 which is of a solenoid type. It is to be understood, of course, that any electrically operated pump may be used. A breaker assembly 41 is associated with the motor shaft 35 to control the energization of the pump 39 which is connected to a suitable source (not shown) by a pipe 42 and delivers fuel through a pipe 43 to a fuel injection nozzle 44 mounted on the air and fuel mixing means 25.

30 The air and fuel mixing means 25 includes a tubular shaped housing member 46 having a substantially closed end portion 47 located in the air supply chamber 19 and an open end portion 48 extended within the combustion passage 21a (Figs. 1 and 3). A mixing chamber 49 located in the closed end 47 is separated from an equalizing chamber 51 by a perforated heat conducting plate 52. The equalizing chamber 51 in turn is separated from the combustion chamber passage 21a by a perforated heat insulating plate 53. Positioned axially of the casing 46 and through the chambers 49 and 51 is a combination heating and igniting unit 54 including a resistance coil 56 supported in a spaced relation within a heat

conducting tube 57 of copper or like material. The casing 46 and the partition plate 52 are also composed of a heat conducting material, such as copper or the like, and are in thermal connection with the combination unit 54 so as to be readily heated thereby. The combination unit 54 operates to heat the air and fuel mixing means 25 to at least a fuel vaporizing temperature to vaporize the fuel supplied thereto by the pump 39 for mixing together with the combustion air supplied by the blower 38, and to ignite such mixture for burning in the combustion chamber 14.

The fuel nozzle 44 is connected with the mixing chamber 49 and is located within the air supply chamber 19. A portion of the air from the air chamber 19 enters the nozzle 44 through ports 55 and travels through the nozzle into the mixing chamber 49. Further air is admitted directly into the mixing chamber 49 from the air supply chamber 19 through apertures 58 arranged about the mounting for the fuel injection nozzle 44. The fuel entering the mixing chamber is heated to at least a fuel vaporizing temperature by the heat generated by the combination unit 54 and is intimately mixed with the air in such chamber, the heat from the heating unit being readily transferred to the casing 46 and plate 52 which are thermally connected with the combination unit 54. This mixing is made more thorough and complete by the turbulence of the air in the mixing chamber. The mixture passes into the equalizing chamber 51 through the apertured plate 52, the equalizing chamber, in conjunction with the insulating plate 53 and a screen structure 65 extended across the perforations in the plate 53, functioning to retard the mixture flow through the conditioning means 25 to reduce the turbulence of the mixture and disperse the same substantially uniformly across the entire open end 48 of the casing 46. A vaporous mixture of substantially uniform fuel characteristics is thus provided at the outlet 43 for ignition by the combination unit 54 which functions as a heat gun. In other words the heat developed by the coil 56 is projected outwardly from the copper tube 57 with the heat generated being dependent upon the watt input to the resistance coil 56. Ignition of the total mixture may be initiated by the prior ignition of a portion thereof which is admitted from the equalizing chamber 51 to a point adjacent the open end of the tube 57 through a tube 59. The vaporous mixture, after ignition, is burned in the combustion chamber 14, the exhaust gases being discharged through the exhaust pipe assembly 26. The blower 38 operates to maintain an air pressure in the air chamber 19 on the order of about two inches of water. Since this pressure alone acts on the combustion chamber burning takes place in the combustion chamber at substantially atmospheric pressure.

It is thus readily apparent from the above description that a quick starting and efficient operation of the heater apparatus is dependent upon a positive operation of the coil 56 to heat the conditioning portion or means 25 to at least a fuel vaporizing temperature. It follows also that the sooner the coil can be operated at an optimum temperature, the less delay there will be in starting the operation of the heater.

Since the conditioning portion 25 is extended within the combustion passage 21a and is thermally connected with the combustion chamber 14 at the combustion chamber inlet 23, the heat of combustion radiated and conducted to the conditioning portion 25 may be sufficient after

initial heater operation to retain the same at a fuel vaporizing temperature, and at least aids the combination unit 54 in its heating function. Since combustion once started tends to ignite further air and fuel supplied for burning the greatest difficulties in the operation of the heater apparatus are encountered during its starting period.

Where a large amount of electrical energy is available for operating the heater air and fuel supply portions, as well as the igniting means, it is a relatively simple matter to provide a coil which will be capable of generating sufficient heat to vaporize the fuel in the conditioning portion 25 regardless of the temperature conditions under which the heater is operated. However, where a battery is utilized as the sole source of power supply for the heater the electrical energy for operating the heater is limited entirely by the available effective capacity of the battery. The effective capacity varies over relatively wide limits defined by a low and high charge condition of the battery. Further variation takes place because of the reduction in the effective capacity with cold temperatures. It is recognized, of course, that batteries vary in size, weight and rating to permit their application to many uses. These considerations of space and weight are particularly important where the heater apparatus is to be used for space or engine heating in airplanes, and particularly in pursuit and bomber planes. The batteries normally used in bomber and pursuit ships have a pressure of twenty-four volts and are rated at about 17 ampere-hours. It may happen, furthermore, that the charging service on these batteries, during their normal use, is rather infrequent, so that the charge of the battery must be utilized to the fullest extent. The power conditions for operating a heater apparatus for aircraft heating are thus very critical, and the power demands on the battery must be reduced to a minimum while concurrently providing for a positive and quick starting of the heater apparatus as well as an efficient operation after starting under very rigorous operating conditions.

With reference to Fig. 4 there is shown a control system of this invention adapted to operate a plurality of the heaters shown in Fig. 1 from a single twenty-four volt battery rated at 17 ampere-hours. Five heaters are illustrated as exemplary of the usual number of heaters required in the heating of the cabin and engines of a four engine bomber or pursuit ship. Each heater includes a similar control circuit indicated generally as 61, only one of which is shown in detail. The battery and heaters, as well as the electrical connections between the battery and heaters must all be of a minimum weight for carrying in the plane. In one embodiment the complete heater unit shown in Fig. 1 has a weight of about eighteen pounds. Weight considerations as to the cable connection between the heaters and the battery requires the use of a relatively light cable 62. In one embodiment this cable is about three hundred feet long and to reduce its weight as much as possible it is made of #14 wire. Although the use of a #14 wire appreciably reduces the weight of the cable it also increases the resistance of the overall control system and in turn the power demand on the battery 60. Because of the emergency conditions under which the heaters in bomber and pursuit ships must operate a quick starting of the heater is essential under all weather and temperature conditions. Since in some localities temperatures on the order

of -40° F. to -50° F. might be encountered a rugged and positive operating control circuit is absolutely necessary.

In Fig. 4 a control circuit 61 for a heater, from the battery 60, includes the cable lead 62 which is connected to a double-throw double-pole switch 63 having corresponding pairs of terminals 64 and 66, and 67 and 68. The switch 63 in a position for starting the operation of the heater completes the circuit for the heating coil 56 from the conductor cable 62 through a switch arm 69, terminal 66, a resistor 71, a conductor 72, the heating coil 56 and a ground connection 73. The motor circuit is also closed at starting and includes from the cable 62 the switch arm 74, terminal 64, conductor 76, the motor 30 and a ground connection 77. The motor 30 and the heating coil 56 are thus concurrently operated when the switch 63 is in its "start" position, the circuit for the pump 39 being open. In order to provide for a heating of the coil 56 to a temperature sufficient to vaporize the fuel admitted into the conditioning or mixing means 25, regardless of the charged condition of the battery 60 and under cold temperature conditions, it is of a construction adapted to be operated when the charge on the battery is reduced to eighteen volts. The resistor 71, series connected with the heating coil, has resistance characteristics providing for a six volt drop. This resistance, of course, can be varied to any amount depending upon the normal operating voltage of the coil 56. With the battery 60 at a normal pressure of twenty-four volts and with the switch 63 in its "start" position only eighteen volts are applied on the heating coil 56 which at this voltage has normal operation. With the battery in a high charge condition, of course, the coil 56 will operate at an overload. However, this overload is not sufficient to seriously injure the coil.

The switch 63 is manually actuated and after it has been held in a "start" position by the operator of the heater apparatus for a length of time to preheat the conditioning means 25 to at least a fuel vaporizing temperature, it is thrown from its "start" position to the "run" position indicated in Fig. 4. During the short time interval required in moving the switch 63 from a "start" to a "run" position the circuits for the heating coil 56 and motor 30 are open. To eliminate any cooling of the coil 56 during this time, the operator, simultaneously with the moving of the switch 63 closes a switch 78 connected by conductor 79 to the cable 62 and by conductor 81 to the conductor 72 intermediate the resistor 71 and the heating coil 56. The circuit for the switch 78 is thus a shunt circuit for the resistor 71. On closing of the switch 78, therefore, substantially the full energy of the battery 60 is applied through this shunt circuit to the heating coil 56. Thus instead of a momentary cooling of the heating coil 56, when the switch 63 is moved from a "start" position to a "run" position there is provided a boost or increase in the energy applied on the coil and in turn an increase in its heat output. On closing of the switch 63 in its "run" position the circuit for the motor is completed from cable 62 through switch arm 74, terminal 67, conductor 82, and terminal 64, the rest of the circuit from the terminal 64 being the same as when the switch 63 is in a "start" position. The circuit for the pump 39 is closed from the cable 62 through switch arm 69, terminal 68, the pump 39, breaker assembly 41, and a ground connection 83. If, after the pump 39 is operated,

combustion takes place in the combustion chamber 14, as will be indicated to the operator by the exhaust gases being discharged from the tail pipe assembly 26 or by the sound of the burning mixture in the combustion chamber, the switch 78 is released to open the circuit of the heating coil 56, the circuit for the motor 30 and the pump 39 remaining closed through the main control switch 63. If, however, combustion does not take place on the admission of fuel into the conditioning means 25 the momentary switch 78 is held closed till combustion has started. Because closing of the temporary switch 78 shorts the resistor 71 from the circuit of the heating coil 56 the full energy of the battery 60 is applied on the heating coil 56 to boost its heat output. Thus even though some free fuel might be in the mixing chamber 49 of the conditioning means 25, as a result of the low heating of the conditioning means by the initial operation of the coil 56, the boost in the heat output of the coil acts to quickly vaporize this free fuel as well as the fuel introduced into the mixing chamber by the continued operation of the pump 39.

Where the effective capacity of the battery 60 is known to the operator to be of a low value, the switch 78 may be closed during the time the switch 63 is at its "start" position so as to assure a positive operation of the coil 56 to heat the mixing means 25 to a fuel vaporizing temperature. This method of operation thus provides for a pre-heating of the conditioning portion by an initial full application of the battery energy on the heating coil with this full energy being applied until after combustion has been started. Under extreme cold temperatures and low battery conditions the switch 78 is initially closed, while switch 63 is open to eliminate the cooling effect of the cold air from blower 38 from action on the conditioning unit 25. When the conditioning unit is heated to a fuel vaporizing temperature the control switch 63 is moved to a "run" position while the temporary switch 78 is held closed. When combustion starts the switch 78 is released.

To stop the operation of the heater it is only necessary to open the switch 63. However, to assure a complete burning of all of the residual fuel in the conditioning unit 45 and combustion chamber 14 the switch from a "run" position is initially moved to its "start" position to operate only the motor 30 and the coil 56. After the residual fuel is burned the switch 63 is opened. The combustion chamber and conditioning unit are thus swept clean of all free and residual fuel to facilitate later starting of the heater. Each of the control circuits in Fig. 4 is operated in a similar manner to that described above to start the operation of a corresponding heater.

In the operation of the heater units in Fig. 4 it may sometimes happen that, after combustion has been started and notwithstanding the fact that the conditioning portion 25 is thermally connected with the combustion portion 14, combustion may be lost in a heater due to a cooling down of the conditioning portion 25 to a temperature below that capable of vaporizing the fuel admitted to the mixing chamber 49. When this occurs the attendant or operator regains combustion in the "lost" heater by operation of its corresponding control circuit in the manner above fully explained. This manual operation of a control circuit to regain combustion, rather than the provision of automatic means to close the operating circuit for the heating coil 56 when

the temperature of the condition means 25 falls below a certain value, is necessary because of the rigorous power demands on the battery 60. In army installations, as well as in some commercial installations, an attendant is always near so that this manual control is no handicap. Because of the plurality of units in operation at the same time it is entirely possible that, with automatic means used to operate the heating coil in response to the combustion conditions in a corresponding combustion portion, several heating coils 56 would be operated at the same time. Even if these coils operated with a current demand of only about $2\frac{1}{2}$ amperes the simultaneous operation of several of them would result in such a severe load on the battery that, with the battery in a low charge condition, this increase in load would stop the operation of the entire installation. If this should occur, all of the heaters would be out and the attendant would be without any specific indication as to the reason for heater failure and as a result would have to check the entire installation before attempting to restart the heaters. However, with a manual control the operator immediately knows which heater has lost combustion. If any of the remaining heaters should go out while he is working on the one which has lost combustion this fact is immediately known to him so that he will have no trouble in making the necessary checks and then operating the control circuits to restart the heaters which have gone out. Thus because of the extreme conditions mentioned both as to the power supply and the temperature conditions under which the heaters must be positively operated there is no advantage obtained from automatic operation and in fact such operation under these conditions would not be practical.

In the modified form of the invention in Fig. 5 a control circuit for a single heater apparatus is illustrated having means for automatically cutting in the heating coil 56 in response to combustion conditions in the combustion chamber 14. In this modification, the power demands on the battery 60 are less critical than in the embodiment of Fig. 4 so that automatic operation can be used advantageously in maintaining operation of the heater and thus appreciably reduce the attention required by the heater during its normal operation. Since the circuits in Figs. 4 and 5 are similar in many respects like reference numbers will be used to designate corresponding parts in these two figures.

The circuits for the motor 30, the heating coil 56 and the pump 39 and the control of their operation by the double-throw switch 63 is similar in all respects to the like circuits in Fig. 4 so that a further description of these circuits and their relative control in the starting and running operation of the heater is believed to be unnecessary. The provision of means for automatically cutting in the heating coil 56, on a failure of combustion in the combustion portion 14, includes a thermostatic switch unit 84 located in a heat exchange relation with the combustion chamber 14 as shown in Fig. 1. The unit 84 includes two normally closed contact arms 86 and 87 which are connected across the terminals 64 and 66 by conductors 88 and 89, respectively. A third contact arm 85 is normally open relative to the contact arm 86 and is connected by a conductor 91 in series with a light 92, which in turn is connected with the ground through a conductor 93. A bimetal arm 94, in the thermostatic switch 84, is

engageable with the contact arm 86 and is movable in response to the heat in the combustion chamber 14 to move the contact arm 86 away from the contact 87 and into substantial concurrent engagement with the contact arm 85.

On initial closing of the switch 63 to a "start" position the circuit of the heating coil is closed from the terminal 66 through the resistor 71, conductor 72, heating coil 56 and the ground connection 73. Although the circuit for the heating coil from the terminal 64 is also closed through the thermostatic switch 84, this switch is without any function in controlling the operation of the heating coil 56 on heater starting. After a pre-heating of the conditioning means 25 by the operation of the heating coil 56 with only a part of the electrical energy of the battery 60 applied thereon, the switch 63 is moved to its "run" position to close the circuits of the motor 30 and pump 39 in all respects similar to the same circuits described above in connection with Fig. 4. The circuit for the heating coil 56 from the battery lead or cable 62 is closed through the switch arm 74, terminal 67, conductor 82, terminal 66, the resistor 71, conductor 72, the heating coil 56 and the ground connection 73. With the heating coil 56 connected in series with the resistor 71 for both the "start" and "run" positions of the switch 63 heating of the conditioning means 25 is accomplished by the use of only a part of the battery energy. Should the coil 56 fail to heat the conditioning means 25 to at least a fuel vaporizing temperature so that combustion does not occur when the fuel pump 39 is operated the temporary switch 78 is closed to shunt the resistor 71 and apply substantially the full energy of the battery 60 on the heating coil. Switch 78 is held closed until combustion starts. It is apparent, of course, that when the heating coil 56 is unable to heat the fuel in the conditioning portion 25 to at least a fuel vaporizing temperature that free fuel might accumulate in the conditioning portion 25 tending to produce a flooded condition therein. By virtue of the closing of the momentary switch 78 there is an immediate boost in the energy supply to the heating coil 56, and in turn in its heat output, so that this free fuel as well as the fuel continuing to be introduced in the mixing chamber 49 by the operation of the pump 39 are all vaporized for burning. When combustion is started as the result of the increase in battery energy applied on the coil 56 the temporary switch 78 is released.

However, since the thermostatic switch 84 is responsive in operation to the combustion conditions in the combustion chamber 14 the coil 56 after release of the switch 78 may continue to operate in series with the resistor 71. This operation of the coil continues until the contact arm 86 moves away from the contact 87 to open the circuit of the heating coil at the thermostatic switch. In moving away from the contact 87, the contact 86 engages the contact 85 to close the circuit of the pilot light 92 through the thermostatic switch, with the lighting of the pilot lamp visually indicating to the operator that combustion has been started and normal operation of the heater accomplished. The pilot lamp circuit from the terminal 67 includes the conductor 82, terminal 64, conductor 88, contact arms 86 and 85, conductor 91, the lamp 92 and the ground connection 93. On a cooling of the combustion portion 14 below a predetermined temperature value corresponding to substantially a fuel vaporizing temperature for the conditioning means 25,

the bimetal 94 is cooled and moves to the left, as viewed in Fig. 5, to permit the contact arm 86 to open the pilot lamp circuit and to close the heating coil circuit through the resistor 71. A going out of the light 92, therefore, indicates to the operator a loss of combustion and the energization of the coil 56 by only a part of the battery energy, the portion of the battery energy to be applied on the coil 56 being determined by the resistance characteristics of the resistor 71. When the effective capacity of the battery is relatively high sufficient heat will be developed by the coil 56 to heat the conditioning means 25 to an optimum temperature so that combustion will automatically be regained. However, if after a period of operation of the heating coil with a reduced battery supply the light 92 does not go on, a low battery condition is indicated to the operator, who then presses the temporary switch 78 to boost the supply of battery energy to the coil 56 to substantially the full energy of the battery. The control system in Fig. 5 thus provides an automatic operation of the heating coil during normal heater operation, means for visually indicating normal heater operation, and a boosting circuit for the heating coil through which substantially the full energy of the battery may be applied to the heating coil to assure its being operated for maximum heat output. The thermostatic switch means 84 is ineffective to control the operation of the coil 56 when the switch 63 is in a "start" position and has a control function only when the switch 63 is in a "run" position. A positive circuit for starting the heating coil is thus completed on closing of the switch 63.

In the modified form of the invention shown in Fig. 6 a thermostatic switch unit 95 is arranged in the control system to control the operation of the heating coil 56 for both the "start" and "run" positions of the switch 63. When the switch 63 is in a "start" position the circuit of the motor 30 from the terminal 64 includes conductor 76, the motor 30 and the ground connection 77. The circuit for the coil 56 from the terminal 64 includes conductor 96, resistor 71, conductor 97, thermostatic switch 95, conductor 98, the heating coil 56 and the ground connection 73. Although a second circuit for the coil 56 is closed from the resistor 71 through conductor 99, a light 92, and conductor 101 to the conductor 98, this circuit is inoperative to energize the heating coil 56 because of the negligible current flow in the conductor 101 permitted by the lamp 92. If, however, the thermostatic switch unit 95 is retained open for some reason, such as ice formations between the contacts 104 and 106 of the switch 95, the coil 56 will not operate and the lamp 92 will light to indicate this condition, the coil 56 at this time remaining cool and functioning merely as a ground in the light circuit.

On moving the switch 63 to its "run" position the circuit for the heating coil 56 from the terminal 67 includes conductor 100, resistor 71, conductor 97, thermostatic switch 95, conductor 98, the heating coil 56, and the ground connection 73. The motor circuit from the terminal 67 includes conductors 100 and 96, terminal 64, conductor 76, the motor 30, and the ground connection 77. The pump circuit from the terminal 68 includes the pump 39, the breaker assembly 41, and the ground connection 83. If on admission of fuel to the conditioning means 25 combustion does not start in the combustion chamber 14, the temporary switch 78 is closed to kick up or boost the heat output of the coil 56 by shunting the re-

sistor 71 through a circuit which includes from the battery lead 62 the conductor 102, switch 78, and the conductor 103 which is connected to the conductor 97. This shunting of the resistor 71 provides for the application of the full battery energy on the coil 56. By virtue of the thermostatic switch 95 being in the coil operating circuit at all times the switch 78 may be held closed until the bimetal contact 104 and the contact 106, of the thermostatic switch 95, are opened in response to the combustion conditions in the combustion chamber 14, the thermostatic switch 95 being carried on the combustion chamber similarly to the switch 84 shown in Fig. 1. On opening of the thermostatic switch 95 the temporary switch 78 is ineffective to control the operation of the heating coil 56. When the thermostatic switch 95 opens sufficient current flows through the lamp 92 to light it and indicate a normal operation of the heater. Although the light circuit, is completed through the coil 56, practically no current flows through the coil because of the current limiting action of the lamp 92. The control system in Fig. 6 thus provides for a positive operation of the heating coil to a desired temperature for a wide range of values in the effective capacity of the battery, and for a controlled operation of the heating coil by thermostatic switch means both during the starting and the normal operation of the heater apparatus.

From a consideration of the above description it is seen that the invention provides a control system capable of providing for a positive starting of a battery-operated heater apparatus including a coil for heating a combustible mixture to a predetermined temperature for burning in a combustion portion. The control system may be used in the operation of a single or a plurality of heater units and operates efficiently to start the heaters for critical power demands on the battery and under temperature conditions as low as -40° F. and -50° F. The complete control system is comprised of a minimum number of parts so that it can be completely checked as to its workability in only a matter of seconds. Provisions in the control system for efficiently and safely operating a heating coil capable of producing a normal heat output at the lowest voltage at which the battery is to operate, assures the use of the battery energy to its fullest extent. This is particularly important in those installations where battery charging facilities are not available, and where charging of the operating battery takes place at infrequent periods. A control system of this invention not only provides for an efficient and positive starting of a heater apparatus under very rigorous operating conditions, but also when the power demand on the battery is not critical or the temperature operating conditions too extreme. Thus it is readily apparent that where a full charge can be maintained on the battery the step in the control system of operating the temporary switch 78 may be entirely eliminated since sufficient heat will always be generated by the heating coil 56 for fuel vaporizing purposes when it is in series connection with the resistor 71.

Although the invention has been described specifically with reference to a battery-operated heater using a coil for heating a combustible mixture to initiate combustion, it is to be understood that this system may be applied to any battery-operated system requiring a booster circuit for an element therein. It is to be under-

stood also that although several preferred embodiments of the invention have been particularly described that it is not to be so limited since alterations and modifications can be made therein which are within the full intended scope of this invention as defined by the appended claims.

I claim:

1. In an electrically operated internal combustion heating system adapted for outdoor operation at low temperatures and having a battery as a sole source of electrical energy and wherein the voltage of said battery is reduced at low temperatures and is also variable within limits defined by the condition of the battery charge; a heating element for preheating fuel for said heating system and producing ignition thereof operated by said battery, a control system for the heating system having a "start" position wherein said heating element is operable to preheat the fuel prior to entrance into the combustion chamber and a "run" position wherein said heating element is operable to preheat the fuel prior to entrance into the combustion chamber and also to ignite the fuel in the combustion chamber, said control system comprising a main switch and an auxiliary switch, said main switch being arranged to select said "start" position or said "run" position and being adapted to apply only a portion of said battery voltage to said heating element, said auxiliary switch being arranged to apply the full battery voltage to said heating element to provide for operation of the heater when said portion of said battery voltage is inadequate to provide the heat required for satisfactory operation of said heating system.

2. In a control system for electrically operated heating apparatus which is adapted to be operated from a battery of variable voltage and includes means defining a combustion chamber, air moving means provided with an electric driving motor and operable to deliver combustion air to said chamber, a fuel feed system including electrical driving means for delivering fuel to said chamber, and electrical heating means for preheating said combustion air and said fuel prior to admission into the combustion chamber and for producing ignition of the fuel within the combustion chamber; the combination which includes a main switch having a "start" position wherein said air moving means and said electrical heating means are connected to said battery for preheating said combustion chamber prior to entry of fuel therein, and a "run" position wherein said air moving means, said fuel feed system and said electrical heating means are connected to said battery for providing combustion in said combustion chamber, said main switch being arranged to apply a portion of the available battery voltage to said heating means, and an auxiliary switch arranged to apply full battery voltage to said heating element to provide for operation of the heater where said portion of said battery voltage is inadequate to produce the heat required for preheating the fuel and providing combustion thereof.

3. In a control system for electrically operated heating apparatus which is adapted to be operated from a battery of variable voltage and includes means defining a combustion chamber, air moving means provided with a driving motor and operable to deliver combustion air to said chamber, a fuel feed system including a pump for delivering fuel to said chamber and electrical driving means therefor, and electrical heating means for preheating said combustion air and

said fuel prior to admission into the combustion chamber and for providing ignition of the fuel within the combustion chamber; a combination which includes a main switch having a "start" position wherein said air moving means and said electrical heating means are connected to said battery for preheating said combustion chamber prior to entry of fuel therein and a "run" position wherein said air moving means, said fuel feed system and said electrical heating means are operatively connected to said battery for providing combustion in said combustion chamber, said main switch being arranged to apply a portion of the available battery voltage to said heating means, an automatic switch operating in response to the temperature of the combustion chamber for disconnecting said electrical heating means from said battery when said main switch is in said "run" position, indicating means for indicating the position of said automatic switch, and an auxiliary switch, arranged to apply full battery voltage to said heating element to provide for operation of said heating apparatus where said portion of said battery voltage is inadequate to produce the heat required for preheating the fuel and providing ignition thereof.

4. In electrically operated internal combustion heating apparatus adapted for operation from a battery having a voltage which is reduced at low temperatures and is also variable within limits defined by the condition of the battery charge; means defining a combustion chamber having an inlet at one end thereof, a fuel conditioning unit disposed at said inlet and provided with a mixing chamber within which fuel and combustion air may be mixed and then introduced into said combustion chamber, electrically driven fuel feeding means for delivering fuel to said mixing chamber, means defining an air pressure chamber at one end of said combustion chamber, enclosing at least a part of said fuel conditioning unit, said fuel conditioning unit having ports therein through which air from said pressure chamber may be admitted to said mixing chamber, electrically driven air moving means for developing an air pressure within said pressure chamber, electrical heating means at least partially disposed within said mixing chamber and operative to heat the fuel and air during the passage through said mixing chamber and to ignite the mixture within said combustion chamber, a control system for said heating apparatus, comprising a main switch having a "start" position in which said air moving means and said heating means are connected with said battery for heating said mixing chamber and said combustion chamber prior to entry of fuel therein, and a "run" position wherein said air moving means, said fuel feeding means and said heating means are operatively connected to said battery for producing combustion in said heating apparatus, said main switch being adapted to apply only a portion of said battery voltage to said heating means, an auxiliary thermostatically controlled switch for disconnecting said heating element from said battery when the temperature in said combustion chamber is sufficient to produce combustion without the use of said heating element, an indicating device for indicating the position of said thermostatically controlled switch and further indicating when said heating device is not providing sufficient heat to produce ignition within the combustion chamber, and a second auxiliary switch arranged to apply full battery voltage to said heating element to provide for

operation of said heater when said portion of said battery voltage is inadequate to provide the heat required for producing combustion.
